UNITED STATES PATENT OFFICE.

WILLIAM H. DUNLAP AND JOSEPH KETCHUM, JR., OF BROOKLYN, N. Y.

HAT-DRYING APPARATUS.

SPECIFICATION forming part of Letters Patent No. 288,987, dated November 27, 1883.

Application filed April 14, 1883. (No model.)

To all whom it may concern:

Be it known that we, WILLIAM H. DUNLAP and JOSEPH KETCHUM, Jr., citizens of the United States, and residents of Brooklyn, in the county of Kings and State of New York, have jointly invented certain new and useful Improvements in Hat-Drying Apparatus, of which the following is a specification.

Our invention relates to certain improvements in the construction and organization of apparatus employed for removing the solvent which is used as a vehicle for applying shellac or other stiffening material to the bodies of felt hats.

15 The object of the invention is to lessen the time required to dry the hat, to secure a more thorough penetration of the stiffening material, and to recover the alcohol, ammonia, or other fluid employed as a solvent.

20 The invention consists in constructing suitable vacuum cylinders or cans for receiving the hats, and providing means for supporting the hats therein, and in applying thereto suitable air or vacuum pumps, by means of which 25 a more or less perfect vacuum may be created in the cylinders. The current of atmosphere and vaporized moisture, as it is withdrawn from the cylinders, is caused to pass through a suitable condensing device, by means of 30 which the solvent is recovered and collected in a liquid form in a suitable reservoir.

In the accompanying drawings, which illustrate our invention, Figure 1 is a view showing the general organization of apparatus, 35 and Fig. 2 represents certain details in the construction of the apparatus.

Referring to the drawings, A' A² A³ represent a series of any desired number of suitable cylindrical cans, preferably of stout material 40 capable of withstanding high pressure, in which the hats are to be placed. The cans are provided with suitable flanged covers, a' a² a³, which are preferably convex, for the purpose of better withstanding the pressure. The bottoms of the cans are likewise convex or globe-shape, and provided with suitable outlet-pipes, b' b² b³. The pipes b connect, through suitable stops, c' c² c³, with a main pipe or exhaust-tube, C. Suitable check-valves, m' m² m³, are inserted 45 in the pipes b, for preventing the air from a can when first applied to the exhausting ap-

paratus from rushing into an exhausted can. These check-valves are preferably constructed as shown in Fig. 2. A plug, n, is provided with a longitudinal perforation, n', which terminates in the valve-seat n². This seat is formed at an angle of about forty-five degrees with the axis of the pipe, in order to insure the closing of the valve-lid n³ through the action of gravity and the resilience of the lid. 55 The said lid n³ is preferably constructed of rubber or similar material, and is attached to the face or seat n² in any suitable manner.

The tube C connects with a coiled tube D, constituting a condenser of well-known construction. The tube D is surrounded by a water tank or cylinder, E, through which a constant stream of cold water is caused to pass by means of the inlet and exit pipes e' e'. The lower extremity of the coil D communicates 70 with an air-tight reservoir, F, in which is collected the condensation of the vapor passing through the tube D. From the upper portion of the tank F a pipe, G, leads to a suitable air or vacuum pump, K, of any construction, adapted to exhaust the air from the tube G, and thus from the pipe C, and any or all of the tanks A communicating therewith.

Suitable supports, H, are employed for supporting the hats in the vacuum-cans A. The 80 supports H each consists of a base-plate or ring, i, carrying a series of uprights, h' h². The hats are designed to be placed upon the support in the manner shown in section in Fig. 1, one hat being placed within the standards h. A tire or 85 ring, j, is placed over and incloses the crown and brim of the hat. A second hat is then placed with its brim resting upon the top of the tire j, and in like manner a tier of any number of hats may be placed in the support 90 H, with a space intervening between each hat.

For the purpose of collecting any moisture which may gather at the bottoms of the cans A, the tubes b preferably lead from the lowest points in the same. These tubes, and likewise 95 the exhaust-pipe C, are preferably inclined sufficiently to furnish the required descent for any fluid which may collect therein, causing it to pass through the vertical condenser D, and thus to reach the reservoir F.

For the purpose of accelerating the removal of the solvent from the hats, the cylinders are 100

heated by means of suitable steam-pipes, L' L^2 L^3 , surrounding their respective bases. The pipes L communicate with any suitable steam-supply, and the temperature of the cylinder may be regulated by means of the valves l . The temperature of the cylinder is preferably maintained at from 90° to 115° Fahrenheit; or the vacuum-cans may be placed in a drying or other suitable room, where the required temperature may be maintained.

Air-valves o may be applied to the cylinders A or to the covers a , for the purpose of permitting the entrance of air when it is desired to remove the covers after the hats have been dried.

In employing the apparatus which we have described, the hats are first saturated with the solution of stiffening material, according to any of the usual processes, and then placed 20 in tiers in the frames H . These frames are then placed within the cylinder A , and the covers a placed over the same. The stop-cock or valve by means of which the particular vacuum-cylinder employed is connected with the exhaust-pipe C is then opened, and a high 25 vacuum will be gradually obtained by means of the pump K . The rapidity with which the vacuum is created may be varied as desired. It is found in practice that the best results are 30 obtained by allowing the hats to remain from one to three hours after a high vacuum is obtained.

We claim as our invention—

1. The combination, substantially as hereinbefore set forth, of a vacuum-cylinder, means 35 of supporting a series of hats therein, and an air-pump connected therewith.

2. The combination of one or more vacuum-cylinders, a series of hats supported therein, 40 means for exhausting the air and moisture therefrom, and a condenser through which

the exhaust from said cylinder is caused to pass.

3. The combination, substantially as hereinbefore set forth, of one or more vacuum-cylinders, means for supporting a series of hats therein, an exhaust-pipe, means for connecting any or all of said vacuum-chambers with said exhaust-pipe, a condenser with which said exhaust-pipe communicates, a reservoir 50 for receiving the condensation from said condenser, and the means for exhausting the air from said exhaust-pipe through said condenser and reservoir.

4. The combination, substantially as hereinbefore set forth, of a vacuum-chamber, means for supporting a series of hats therein, a tube leading from the lower extremity of said chamber, an exhaust-tube, a condenser with which said exhaust-tube is connected, a reservoir for 60 receiving the condensation from said condenser, and means, substantially such as described, for heating said cylinders.

5. The combination, substantially as hereinbefore set forth, of a series of vacuum-chambers, means for supporting a series of hats therein, a tube leading from the lower extremity of each of said chambers, a check-valve included in each of said tubes, an exhaust-pipe with which all of said tubes communicate, 70 and means, substantially such as described, for withdrawing the air from said exhaust-pipe.

In testimony whereof we have hereunto subscribed our names this 12th day of April, A. D. 75 1883.

WILLIAM H. DUNLAP.
JOSEPH KETCHUM, JR.
